UNITED STATES PATENT OFFICE.

ELIE GRANAT, OF PARIS, FRANCE, ASSIGNOR OF ONE-HALF TO BENARD BARBIER & TURENNE, OF PARIS, FRANCE, A FIRM.

SEARCH-LIGHT APPARATUS.

1,303,656.

Specification of Letters Patent.

Patented May 13, 1919.

Application filed December 22, 1917. Serial No. 208,482.

To all whom it may concern:

Be it known that I, ELIE GRANAT, a citizen of Russia, residing at Paris, France, have invented Improvements in Search- 5 Light Apparatus, of which the following is a specification.

This invention has reference to search light apparatus and has for its object to provide improved mechanism for effecting the 10 horizontal and vertical movements of the luminous rays in order to direct them in horizontal and vertical searching and pointing operations.

The improved mechanism is so constructed 15 and arranged that operation of the mechanism to effect adjustment of the luminous rays in a horizontal plane does not cause any alteration in the vertical adjustment of the luminous rays.

20 For this purpose according to the invention an irreversible unit of the mechanism for vertically adjusting the luminous rays is arranged upon the movable part of the apparatus in such a way that the adjustment 25 of the luminous rays in a horizontal plane has no other effect upon the mechanism for adjustment of the rays vertically than to cause the controlling hand wheel of the vertical adjusting mechanism to rotate without 30 however the axis of the luminous rays being displaced in altitude.

The accompanying drawings show a construction of search light apparatus embodying the invention merely by way of demonstrative but not restrictive example.

Figures 1 and 1^a, read together, illustrate the apparatus in vertical section following planes passing, as to the left half of the figure, through the axis of the hand wheel controlling the vertical adjustment of the rays and, as to the right half, through the axis of the clutch mechanism for throwing the mechanism controlling the horizontal adjustment out of gear, parts of the apparatus 45 being removed or broken away for the sake of clearness.

Fig. 2 is a sectional plan of part of the mechanism for controlling the horizontal adjustment of the rays.

50 Figs. 3 and 4 show in vertical section corresponding to the line 3—3 of Fig. 4 and in horizontal section according to the line 4—4 of Fig. 3 respectively parts of the mechanism for controlling the vertical adjustment of the 55 rays.

a, Fig. 1^a shows the base or mounting of

the apparatus in which in the usual manner, there is arranged to rotate about a vertical central axis, a sleeve *b* to which is rigidly fixed an upper movable plate *c* that carries the bracket or bifurcated stirrup *d* in the arms of which the projector *e* can turn about a horizontal axis, on two pivots of which only one is shown at *e*¹. Only a small part of the projector *e* is shown.

60 Direction of the luminous rays in a horizontal plane is controlled through gearing comprising an irreversible transmission gear unit, by means of a hand wheel *f*, Fig. 2. The said gearing comprises toothed pinions *f*¹ *f*², engaging one into the other, a worm *f*³, Fig. 1^a, keyed upon the shaft of the pinion *f*² and engaging with a worm wheel *f*⁴ fixed upon a vertical shaft *f*⁵, and a toothed pinion *f*⁶ gearing into a ring of teeth *c*¹ 75 fixed to the movable plate *c*.

70 A cone clutch *g* is mounted on the shaft *f*⁵ and adapted to be actuated from the exterior by means of a bell crank lever *g*¹ which is rocked by a screw *g*² that is rotated in a part forming a fixed screw nut by means of a hand wheel *g*³. The worm wheel *f*⁴ can consequently be disconnected at will from the shaft *f*⁵ in order that large and rapid displacements of an angular nature 85 can be given to the luminous rays for the preliminary search for the direction of an object, the final or exact definition or pointing being effected by operating the hand wheel *f* after having reengaged the 90 worm wheel *f*⁴ with the shaft *f*⁵.

95 Controlling the height of the luminous rays is effected by means of gearing comprising an irreversible transmission unit, certain elements of such gearing being on the stationary part of the apparatus, and the others being mounted upon that part of the apparatus which carries the projector and is movable in a horizontal plane. This gearing is arranged in the following manner:— 100 A control hand wheel *h* operates, by means of toothed pinions *h*¹, *h*², a bevel pinion *h*³ that gears into a bevel wheel *h*⁴ mounted upon a vertical hollow shaft *h*⁵ located within the sleeve *b* hereinbefore mentioned and 105 arranged coaxial therewith. Fixed on the upper end of the hollow shaft *h*⁵ is a bevel wheel *h*⁶. All these members, as may be seen, are mounted in the stationary part of the apparatus and the movement thereof is 110 transmitted, through a bevel wheel *i* gearing into the bevel wheel *h*⁶ to an irreversible

unit comprising a worm and worm wheel enclosed within a casing *j* mounted on the movable plate *c*, (see Figs. 1, 3 and 4).

Upon the shaft carrying the bevel wheel *i* 5 is keyed a worm *i*¹, Fig. 3, gearing into a worm wheel *i*² fixed upon a shaft on which is also keyed a bevel wheel *i*³. The bevel wheel *i*³ gears into a bevel wheel *i*⁴ the shaft of which transmits through shafts *i*⁵, *i*⁶ and 10 Cardan joints *i*⁷, *i*⁸ movement to a bevel pinion *i*⁹ that gears into a toothed bevel sector *e*² fixed upon the pivot *e*¹ of the cylinder projector *e* of the search light (see Fig. 1). The jointed shafts *i*⁵ or *i*⁶ are located within 15 the bracket or bifurcated stirrup *d* and consequently protected against dust and rain.

A cone clutch *k* similar to the disconnecting gear *g* of the mechanism for controlling the horizontal pointing of the searchlight 20 and adapted to be manipulated from the outside by means of a hand wheel *k*¹, enables the bevel pinion *i*⁹ to be disengaged at will from the shaft *i*⁶, for the preliminary searching movements of the rays.

25 The hereinbefore described arrangement of the height controlling mechanism affords the great advantage of preventing the altitude of the rays from being interfered with when the apparatus is being moved for horizontal adjustment or searching. As a matter of fact as the irreversible unit worm *i*¹ and worm wheel *i*² is arranged on the movable plate *c* of the apparatus, the bevel wheel *i* when the horizontal adjustment control 30 mechanism is in use, carries around the bevel wheel *h*⁶ and, through the parts *h*⁶, *h*⁵, *h*⁴, *h*³, *h*², *h*¹ of the transmission gearing, rotates the controlling hand wheel *h* of the vertical adjustment control mechanism. In horizontal 35 movements therefore, the hand wheel *h* rotates without however the axis of the luminous rays undergoing any displacement as regards altitude.

The control hand wheels *f* and *h* each are, 40 or may be, fitted with a sprocket rim to permit of a chain drive operated from the ground if desired for effecting the adjusting movements both for direction and height. The chains may, moreover have 45 special links arranged at distances apart corresponding to one turn of the hand wheels so that the amount of movement may be easily distinguished by touch at night time.

50 It will be readily understood that the invention is not strictly limited to the exact arrangements hereinbefore described and shown in the accompanying drawings, but that the structural details may be variously modified in practice according to circumstances.

What I claim is:—

1. In searchlight apparatus, a stationary

part, an angularly movable portion, mechanism for moving said movable part to move 65 the luminous rays about horizontal planes, and mechanism for moving the luminous rays vertically comprising an irreversible unit arranged upon the movable portion of the apparatus and a shaft for actuating said 70 unit, said shaft being mounted to rotate in the stationary part of the apparatus about an axis coincident with the axis of said movable portion, so that horizontal adjustment does not affect the altitude of the luminous 75 rays.

2. In searchlight apparatus, a stationary mounting, a projector, or carrier in which said projector is mounted to rock vertically, said carrier being mounted to rotate in a 80 horizontal plane on said mounting, a centrally arranged shaft arranged to rotate in said mounting, means carried by said mounting adapted to rotate said shaft, a bevel wheel on the upper end of said shaft, a 85 bevel pinion gearing into said bevel wheel and carried in bearings fixed to said carrier, transmission gear mounted on said carrier including an irreversible unit connecting said bevel pinion to said projector and 90 adapted to rock said projector, and means for rotating said carrier on said mounting.

3. Searchlight apparatus, comprising a fixed mounting, a carrier mounted to rotate in a horizontal plane on said mounting, 95 a projector mounted to rock in said carrier, gearing carried by said mounting for rotating said carrier, gearing partly arranged in said mounting and partly arranged in said carrier for rocking said projector, said last 100 named gearing including an irreversible unit, and independent means on said mounting for operating each of said gearings.

4. Search light apparatus as claimed in claim 1 comprising a clutch associated with 105 each of said mechanisms, and operating means for said clutches.

5. In search light apparatus, a fixed mounting, a vertical sleeve mounted to rotate in said mounting, a plate fixed to the top of said sleeve, a stirrup shaped bracket fixed on said plate, a projector pivoted in the arms of said bracket, a vertical shaft mounted to rotate in said sleeve, a bevel wheel fixed to the lower end of said shaft, means on said 110 mounting for rotating said vertical shaft, means on said mounting for rotating said plate and carrier, a bevel wheel at the top of said vertical shaft, and gearing mounted in said bracket including an irreversible unit 115 between the said bevel wheel at the top of said shaft and said projector, substantially as described.

Signed at Paris, France, this 23d day of November, 1917.

ELIE GRANAT.
